UNITED STATES PATENT OFFICE.

REINHOLD A. NORLING, OF AURORA, ILLINOIS, ASSIGNOR TO AURORA AUTOMATIC MACHINERY COMPANY, OF AURORA, ILLINOIS, A CORPORATION OF ILLINOIS.

ELECTRIC DRILL.

1,158,543.

Specification of Letters Patent.

Patented Nov. 2, 1915.

Application filed September 18, 1913. Serial No. 790,577.

To all whom it may concern:

Be it known that I, REINHOLD A. NORLING, a citizen of the United States, and a resident of Aurora, in the county of Kane 5 and State of Illinois, have invented certain new and useful Improvements in Electric Drills; and I do hereby declare that the following is a full, clear, and exact description thereof, reference being had to the accompanying drawings, and to the letters of reference marked thereon, which form a part 10 of this specification.

This invention relates to improvements in electrically operated tools and more particularly to that class of electrically operated tools embracing drills and implements of like nature of a portable character.

The object of this invention is to provide a construction for tools of the character described, which embraces, among other things, such features as high efficiency, extreme durability and exceptional power in proportion to its size and weight. To accomplish this end, I propose to unite a suitable motor of rugged construction, provided with an adequate and suitable fan designed to prevent overheating of the motor parts under the most extreme conditions of operation, and a spindle or tool holding member provided with ample and compactly arranged bearings.

My invention will, therefore, consist in the matters hereinafter described and more particularly pointed out in the appended 35 claims.

In the drawings, Figure 1 is a view in longitudinal section of an electric drill embodying my invention, Fig. 2 is an enlarged cross-sectional view taken on line 2-2 of Fig. 1, Fig. 3 is a view in cross-section taken on line 3-3 of Fig. 1, Fig. 4 is a view in cross-section taken on line 4-4 of Fig. 1, Fig. 5 is an enlarged view in end elevation of the cover removed from the drill, Fig. 6 is an enlarged view in side elevation of the said cover removed from the drill; Fig. 7 is an enlarged view in longitudinal section of the switch showing the details of construction of the same.

50 Referring to the construction shown in the

accompanying drawings, the tool constituting my invention comprises the several main parts as follows: A cylindric casing 1, containing the motor field coils, armature, brushes, brush holders, and ventilating fan; 55 a gear casing 2 supporting the tool spindle 3 and containing certain gears interposed between the motor armature shaft and the said tool spindle; a center plate or partition wall 4 between said motor casing 1 and gear casing 2 supporting suitable bearings for the gears, spindle, and armature shaft, and a handle 5 rigidly secured, by preference, to the motor casing 1, and containing a manually operable switch 6, and other suitable 60 electrical connections. The motor casing 1, center plate 4 and gear casing 3 are secured together by means of a plurality of cap screws 7 extending through lugs 1^a and 2^a formed on the adjacent edges of the motor 65 and gear cases, respectively, and through the edges of the center plate.

Referring more in detail to the construction of my device, the motor casing 1 is cylindrical in shape and preferably constructed 75 of aluminum or similar light metal. Within the central portion of the motor casing is supported the field magnet 8, the same being held securely in place by means of longitudinal ribs 1^b formed on the inner surface of the casing 1, and a clamp screw 8^a extending through the lower part of the casing adjacent to the handle 5. Extending longitudinally in the motor casing is the armature comprising an armature shaft 9 80 upon which is mounted the armature core 10 and commutator 10^a. The said armature shaft 9 is rotatably mounted within the motor casing in the following manner: The rear portion of the said casing is provided 85 with an outwardly extending, vertical bridge member 11 integral with said casing and forming on either side comparatively large openings communicating with the interior of the casing. Within the central 90 portion of said bridge member is formed an annular depression into which is fitted the outer antifriction bearing 12 for the armature shaft. This bearing comprises two concentrically arranged collars or cage mem- 100

bers 12^a and 12^b. The inner collar 12^a is preferably pressed upon the reduced extremity of the armature shaft 9 and secured in position by means of a washer 13^a and 5 nut 13, the latter having screw-threaded engagement with the extremity of the said shaft 9. The outer collar 12^b is loosely fitted within the depression formed within the bridge member in order to permit the 10 desired end play of the armature shaft. Within the adjacent surfaces of the collars 12^a and 12^b are formed concentric grooves which form a bearing race for a plurality of anti-friction bearing balls 14. The inner extremity of the shaft 9 is provided with a 15 partially threaded tapered portion 9^a, upon which is mounted a small pinion 16 having a diameter which is by preference substantially equal to that of the shaft so that in reality the same may form a continuation 20 of the shaft having gear teeth cut on the end portion thereof. The pinion 16 extends through an aperture 4^b in the center plate and projects beyond the same into the 25 gear casing 2. An anti-friction bearing 17 supports the adjacent end of the shaft and is retained within a depression formed in the center plate 4 and within the margin of the said aperture 4^b. This bearing 30 is similar in construction to the bearing 11 hereinbefore described, and for that reason the same need not be again described in detail. Furthermore, in view of the fact that I have used this type of anti-friction bearing 35 in the construction of several parts of the device, the same in each case will henceforth be merely referred to as antifriction bearings, and a detail description of the same being omitted for the reason before indicated. Immediately adjacent to the 40 outer extremity of the armature shaft 9 and constituting a part of the armature is the before mentioned commutator 10^a. Within the space surrounding the commutator 45 are contained the brushes and component parts as follows: A brush plate 18, (Fig. 2) composed of fiber or like suitable insulating material, is mounted within and concentrically with the casing adjacent to its outer end. The said brush plate 18 has 50 the form of a ring through which extends the said commutator 10^a, said brush plate being provided with a plurality of elongated curved slots 18^a, 18^b, through which extends screws 19, 19. The said screws have 55 screw-threaded engagement with the lugs 20, 20 integral with and located at the outer ends of two of the longitudinal ribs 1^b upon the inner surface of the motor casing 1. Mounted upon the brush plate 18 are the 60 brush holders 21, 21. These are secured in place upon the brush plate by means of screws 22^a, 22^b. The brush holders 21, 21, are shown as parallel and vertically ar-

ranged plates provided at their central portions and adjacent to the commutator with retaining slots 21^a, 21^b, within which are held the contact brushes 23, 23 extending inwardly substantially at right angles to the brush holders and engaging the surface 65 of the commutator. Staples 23^a, 23^b, are further provided to hold said brushes within the retaining slots. The said screws 22^a, 22^b, at the corresponding extremities of the brush holders also act as terminals for the 70 electrical connections leading to the brushes. Pivots mounted upon the brush plate above and below each of the brush holders are brush arms 24, 24, which are pivotally secured at a short distance from the face 75 of the brush plate by means of the said screws 22^b before mentioned as extending through the oppositely disposed ends of the brush holders. These brush arms bear upon the outer ends of the brushes, a constant 80 pressure being applied thereto by means of coil springs 24^a, 24^b, (Fig. 1) surrounding the screws 22^b and secured at their ends to the said brush holders and brush arms. The entire brush mechanism can be shifted by 85 loosening the screws 19, 19, and rotating the brush plate 18 so as to vary the brush lead when desired.

Surrounding the entire end portion of the motor casing and including the bridge member 11, is a cup-shaped cap or brush cover 25 (Figs. 5 and 6) of sheet metal. The margin of said cover 25 abuts against a shoulder formed upon the motor casing 1 by an annular flange 1^c upon the outer surface thereof, and is secured in position in the following manner: Immediately above and below the central portion of the bridge member 11 are studs 27^a and 27^b, which have screw-threaded engagement with the said bridge 95 member. These studs extend through apertures in the brush cover, one of said studs 27^a being of considerable length and adapted to carry a feed handle 28 which screws upon the stud tightly against the cover. The 100 other stud 27^b is provided with a nut 29 also fitting against the cover. The central portion of the brush cover is pressed outwardly to form a depression 25^a adapted to accommodate the extremity of the armature 105 shaft 9 and nut 13. The portion of the brush cover adjacent to the depression 25^a bears against the collar 12^a of the antifriction bearing and acts to hold the said collar in place. A suitable cover 25^b is provided 110 upon the portion of the brush cover forming the said depression and normally covers an oil hole extending through the brush cover. The brush cover is further provided with a plurality of small holes 26 for the 115 purpose of admitting air to the interior of the motor casing 1. The brush cover 25^b is provided 120 upon the portion of the brush cover forming the said depression and normally covers an oil hole extending through the brush cover. The brush cover is further provided with a plurality of small holes 26 for the 125 purpose of admitting air to the interior of the motor casing 1.

At the inner end of the interior space of

the motor casing is a fan 29, the same comprising a plurality of comparatively short fan blades 29^a, which move in an annular space in close proximity to the center plate 4 and the wall of the motor casing. The hub 29^b of the fan is mounted upon the armature shaft by means of a pin 30 extending through the said hub and shaft. Within the wall of the motor casing is formed an annular channel 31 which surrounds the periphery of the fan. Communicating with the channel 31, and extending through the casing 1 are a plurality of annularly arranged holes 31^a approximately surrounding the fan. The purpose of these holes is to form a means of egress for air which is drawn through the motor casing by the fan, the air entering the holes 26 of the brush cover and passing through the motor casing by means of the spaces formed between the field coils and the wall of the casing.

The current of air induced by the fan carries away the heat generated by the motor, thus preventing the overheating of the same.

Referring now to the construction and arrangement of the gearing and spindle contained within and supported by the gear casing and centerplate: A tool spindle 3 is provided which consists of a hollow shaft having its axis parallel to the axis of the armature shaft and offset therefrom. The said tool spindle is provided at its inner end with an enlarged cylindric portion having the form of an annular flange 3^a, which surrounds a centrally disposed annular cavity. Encircling and in concentric relation to this flange 3^a is an internal spindle gear 33, the same preferably comprising a cup-shaped gear member 32, opening toward the center plate and formed integral with the spindle at a point adjacent to the inner portion of the flange 3^a. Within a depression formed upon the inner surface 45 of the gear member is retained a gear ring in which are cut the gear teeth of the internal gear 33. The drill spindle 3 is rotatably mounted within the gear casing by means of bearings arranged in the following manner: Within the outer portion of the cavity formed by the annular collar 3^a is located a roller bearing 34, comprising a plurality of cylindric rollers 34^a loosely retained within a cage 34^b. The said roller bearing is interposed between and bears upon the elements as follows: A bushing 35 is fitted tightly to the flange 3^a and surrounds the bearing forming the outer bearing surface for the roller 34^a. The inner bearing surfaces of the roller 34^a engage a cylindric bearing guide 36 which is in the form of a stub-shaft one end of which projects a short distance into the cavity of tool spindle and the opposite end of which is

supported by means of a boss 37 integral 65 with the center plate 4, which boss has a central bore into which the last mentioned end portion of said guide extends. The guide 36 is further provided with an annular flange or collar 36^a bearing against 70 the face of the boss 37 and which acts as a retainer for the retaining ring 34^b of the roller bearing 34 and serves to prevent longitudinal movement of the guide 36 in a direction away from the work or tool point. 75 Within the said cavity of the tool spindle and adjacent to the roller bearing 34 is a thrust bearing comprising parts as follows: A ball race 38 fits tightly within the inner extremity of the cavity formed by the flange 80 3^a of the hollow spindle and comprises a circular plate provided with a concentric groove within which are retained a plurality of bearing balls 39. The balls are interposed between the ball race 38 and a circular thrust plate 40 loosely mounted within the cavity, and which plate abuts against the end face of the guide 36. By this construction the thrust bearing acts to transmit the end thrust of the tool spindle 90 to the guide 36 and, in so doing, diminishes the friction resulting from the endwise force exerted by the spindle during the operation of the drill or other tool carried in the spindle. The tool spindle is further provided with an external roller bearing 41 surrounding the same at substantially its central portion and between the annular flanged portion 3^a of the spindle and the end portion of the wall of the casing 2. 100 This roller bearing is of the usual construction comprising rollers 42 surrounding the shaft and bearing against bushings 43 and 44 secured to the spindle and within an annular recess formed in the wall of the casing 2, respectively, and roller thrust plates or rings 45, 45, against which the ends of the rollers abut and which are interposed between the ends of said rollers and the shoulder 3^b of the spindle and the end wall 110 of the casing 2. The tool spindle projects through an aperture formed in the end wall of the gear casing, there being provided at that point a stuffing box 46, having screw-threaded engagement with the inner surface of an annular flange 2^b projecting outwardly from the end wall of the casing and surrounding the aperture therein through which the tool spindle extends. Within a bore formed at the inner end of 120 said stuffing box is retained a packing ring 47 provided for the purpose of preventing the escape of lubricating oil from the interior of the said casing 2. A central bore or socket extends through the outer portion of 125 the spindle and communicates with the cavity at its inner end. The said socket is of a uniform diameter and is provided at

its inner end with a plurality of longitudinally extending and diametrically arranged inwardly projecting ribs or projections 3^c (Fig. 4). This central bore or socket is 5 adapted to hold the drill chuck 48, within the jaws 48^a of which is tightly held the drill or similar tool. The chuck 48 is provided with a chuck shank 49 having a cylindrical forward portion of uniform diameter adapted to fit snugly within the said 10 socket of the drill spindle. The shank terminates a short distance from the ball race 38 of the thrust bearing, and is provided at its extremity with longitudinal grooves 15 49^a adapted to admit and engage the ribs 3^c of the tool spindle, thereby serving to prevent the rotation of said shank within the drill spindle. In order to retain the drill 20 chuck in its socket, the following means are provided: Upon the outer end of the drill spindle is mounted a locking nut 50 having screw-threaded engagement with the threaded extremity of the said spindle. The shank of the drill chuck is provided with 25 an annular flange 49^b against which the lock-nut bears, thus by tightening the lock nut upon the said flange the chuck 48 is held in place. The flange 49^b also acts to limit the distance which the shank of the 30 drill chuck may enter the drill spindle socket.

and 53, said contact disk being separated slightly from said terminal blocks by means of fiber faces 56. Within each of the terminal blocks are embedded two terminals 57, the same being similarly arranged diametrically as well as longitudinally. These 70 terminals comprise parts as follows: A terminal socket 58 extends through the terminal block and opens toward the center disk 54. Within the socket is a terminal plunger 59 provided with a rounded contact point and an interior recess in which is retained a coiled spring 60 acting to constantly force the plunger from its socket. A terminal screw 61 connects the conductor wires 62 75 to the terminals 57. The center disk 54 is provided with contact blocks 54^a composed of a conductive metal and extending through the same so located as to engage the corresponding pairs of terminals in one position 80 of the contact disk. The said contact disk is further provided with radial lugs or operating fingers 54^b which project through slots 55, Fig. 2, formed in the upper margin 85 of the handle and beyond the same. The lugs are of sufficient length so that the same may be conveniently engaged by the thumb or finger of the operator and rotated through a distance sufficient to make or break the 90 electrical connection between the terminals. 95

Within the lower cup-shaped portion of

Extending at right angles to the longitudinal axis of the motor casing, is a hollow cylindric extension 1^a integral with said motor casing. The said extension is provided with a circular marginal flange to which is rigidly secured the before mentioned tool handle 5, the same also extending at right angles to the axis of the motor casing. The handle comprises a tubular member having two cup-shaped extremities and a smaller intermediate central portion serving as a grip for the hand of the operator. At the upper extremity of the handle is provided a flange 5^a registering with the flange of the extension 1^a of the motor casing and through which extend cap screws 51, 51 by means of which the said handle is secured to the motor casing. Within the handle and adjacent portion of the extension 1^a are contained the switch 6 and connections. The said switch is preferably constructed as follows: Two stationary terminal disks or blocks 52 and 53, Fig. 7, are secured in the lower portion of the extension 1^a of the motor casing and in the adjacent cup-shaped extremity of the handle 5, respectively. These terminal blocks are composed of insulated material, such as porcelain or hard rubber or other suitable material and are separated by a movable contact disk 54 of like material and which is pivoted in position by means of a center pin 55 extending through the same and pivotally mounted within sockets formed in the stationary terminal blocks 52 and 53. Within the lower cup-shaped portion of the handle is an electrical connection block or socket 63 connected with the terminals 57 of the terminal block 53 of the switch by means of the conductors 62. The said connection block 63 is adapted to receive a suitable connecting coupling or plug or any desired or ordinary type attached to a sufficient length of wire whereby electric current may be supplied to operate the device. By the construction of an electric drill as herein described and illustrated, several advantageous results are obtained, chiefly among which may be mentioned the ease and convenience with which the parts may be reached and removed when it is desired to renew or replace broken or worn parts; the compact manner in which the rotating parts are mounted, and the novel and efficient manner of providing bearings for the said rotating parts; portability and efficiency in operation. It is to be noted that in the arrangement of the motor, the brushes and brush holders, which ordinarily require frequent attention, are located so that they are not only protected but easily accessible by merely removing the brush cover 25, which operation does not require the necessity of disturbing any other part or parts of the device. The brush cover 25 further acts to protect the brushes and other parts from injury and prevents the entrance of dirt into the motor casing, and at the same time motor casing is amply provided with holes to admit air therein.

5 A further feature of this construction is that the pinion 16 is mounted on the armature shaft so that the same can be easily removed without removing or replacing the armature shaft or disturbing the motor in any way, in case the pinion should be broken. Nor would the fan be disturbed by this operation, for the reason that the same is connected with the armature shaft and not to the pinion.

10 Another advantage of particular importance is the form of bearings used in connection with the internal gear and the drill spindle, consisting of the stationary guide 15 36 secured to the center plate, and the antifriction bearings mounted upon them. This construction not only permits the external gear and drill spindle to have a very desirable long, adequate, well-braced and well-balanced bearing adapted to minimize the 20 loss of power by friction thereby enabling the maximum degree of efficiency or power to be obtained, but makes it possible to locate the bearing entirely within the gear and 25 spindle, the result being that a very light and compact arrangement is obtained, whereby the size of the gear casing is materially reduced, and the extra weight of bearings likewise reduced to a minimum.

30 The manner of securing the chuck within the drill spindle socket has also its advantages over the ordinary tapered socket and taper fitting chuck or tool, for it is to be observed that the shank of the chuck fits 35 snugly and in accurately centered position within the socket and can be set or removed entirely without the use of tools, by merely removing the lock nut 50 with the fingers. It is impossible for the chuck to stick in the 40 drill socket as is often the case in a tapered socket and shank which condition requires the use of a tool and necessitates a loss of time. The construction of the handle and 45 the location of the switch and electrical connections are further features to be mentioned. The switch is entirely inclosed within the handle and motor casing thereby being fully protected from breakage, and is in such a position that the operating fingers are easily accessible by the hand of the 50 operator grasping the tool. Again, by mounting a socket at the outer end of the handle and providing a conductor extending to the switch, the tool has a complete and 55 protected controlling switch and attachments, thus dispensing with the necessity of having an undesirable length of wire connected with the tool which must be transported, or as is more often the case, dragged 60 over the floor when moving the tool from one place to another.

I am aware that these advantages mentioned together with others may be obtained by modifying the details of construction of 65 my device without departing from the spirit

of my invention and for that reason I do not wish to be limited to the specific construction herein described and illustrated in the accompanying drawings, except in so far as it is specifically pointed out in the 70 appended claims.

I claim as my invention:

1. In an electric drill, the combination of 75 a motor casing provided at one end with a bridge member, a motor mounted in said motor casing and provided with an armature shaft, an antifriction bearing for said armature shaft mounted in a depression formed in said bridge member, and a perforated cover extending over the end of the 80 motor casing and engaging said antifriction bearing.

2. In an electric drill, the combination 85 of a motor casing provided at one end with a bridge member, a motor mounted in said motor casing, and provided with an armature shaft having at one end, an antifriction bearing mounted in a depression formed in said bridge member, a perforated cover extending over the end of the motor casing 90 and engaging said bearing, a stud extending through said cover and anchored in said bridge member, and a feed handle carried by said stud.

3. In an electric drill, the combination 95 of a motor casing provided at one end with a bridge member, a motor mounted in said casing and provided with an armature shaft, a tool spindle operatively connected with said armature shaft, antifriction bearings 100 for said armature shaft mounted in a depression formed in the bridge member, a perforated cover extending over the end of the motor casing and said depression, a stud extending through said cover and anchored 105 in said bridge member, and a feed handle carried by said stud and bearing against said cover.

4. In an electric drill, the combination of 110 a motor casing, provided at one end with a bridge member, a gear casing at the other end, a center plate interposed between said motor casing and said gear casing, a motor mounted in said motor casing and provided with an armature shaft, contact brushes supported in said motor casing adjacent to said bridge member, a fan secured to said armature shaft adjacent to said center plate, said casing being provided with exhaust apertures adjacent to said fan, antifriction bearings for said armature shaft mounted in said bridge member and center plate, and a perforated cover extending over the end of the motor casing and secured to said bridge member.

5. In an electric drill, the combination of 120 a casing provided at one end with a bridge member, an electric motor mounted in said casing and provided with an armature shaft, a bearing for said armature shaft compris- 125

ing an inner member secured to said shaft, an outer member loosely retained in an annular depression of said bridge member and a plurality of bearing balls interposed between said members, and a perforated cover extending over the end of the motor casing and secured to said bridge member and bearing against the outer bearing member to hold the same in place.

10. 6. In an electric drill, the combination of a casing open at one end and provided with a bridge member integral with the casing, a motor in said casing, a tool spindle journaled in said casing and operatively connected with said motor, anti-friction bearings for the armature shaft of said motor mounted in said bridge member, a perforated cover extending over the said open end of said casing and exterior to said bridge member and provided with a central depression the margin of which bears against the said bearing studs extending through said cover and anchored in said bridge member, and a feed handle carried by one of said 25 studs in axial alignment with the tool spindle.

7. In an electric drill, the combination of a casing open at one end and provided with a bridge member integral therewith and extending over said open end, an electric motor within said casing, a gear casing mounted at the other end of said motor casing, a center plate separating said motor and gear casings, a tool spindle journaled in said gear casing and operatively connected with the 30 motor, a spindle bearing guide supported in said center plate, antifriction bearing members for the armature shaft in said center plate and said bridge member, and a perforated cover extending over the open end of 35 said motor casing and secured to said bridge member, said cover bearing against one of the armature shaft bearing members to hold the same in said bridge member.

8. In an electric drill, the combination of 40 a motor casing open at one end provided with a bridge member integral with the motor casing, a gear casing at the other end, a tool spindle journaled in said gear casing and operatively connected with said motor, a center plate separating said motor and gear casings, an electric motor mounted in said gear casing, antifriction bearings for the armature shaft of said motor in said center plate and bridge member, a perforated 45 cover extending over the said open end of said motor and exterior to said bridge member, studs extending through said cover and anchored in said bridge member, and a feed handle carried by one of said studs in axial alignment with the tool spindle.

9. In an electric drill, the combination of 50 a casing, a motor mounted in said casing, a tool spindle journaled in said casing in operative connection with said motor, and a 55 hollow non-rotative handle rigidly mounted

upon and communicating with said casing and extending at right angles to the axis of said tool spindle, and a switch mounted in the adjacent portions of said casing and handle, a socket member mounted in the 70 outer end portion of the handle and conductors connecting said switch and socket member.

10. 10. In an electric drill, the combination of a casing, a motor mounted in said casing, a 75 tool spindle journaled in said casing in operative connection with said motor, a feed handle mounted upon said casing in axial alignment with said tool spindle, and a tubular non-rotative handle rigidly secured to, and extending from, said casing at right angles to the axis of the tool handle, said handle communicating with said casing and provided with a slot adjacent to said casing, a switch mounted within said handle provided with an operating finger extending outwardly through said slot, and a socket member mounted in the outer extremity of 80 said handle and in electrical connection with said switch.

11. In an electric drill, the combination of a casing provided with an extension projecting from said casing at right angles to the axis thereof, said extension being provided with an opening communicating with said casing, a tool spindle mounted in said casing and operatively connected with said motor, a hollow non-rotative switch handle rigidly connected with said cylindric extension and communicating with the casing, a 95 switch mounted in said handle and adjacent portion of said extension, and a socket mounted in the outer end of said handle and electrically connected with said switch.

12. In an electric drill, the combination of a casing, provided at one end with a bridge member, a motor in said casing, a tool spindle journaled in said casing and in operative connection with said motor, a perforated cover extending over the end of the 100 casing and secured to said bridge member, a feed handle secured in said bridge member, a non-rotative hollow handle mounted on said casing at right angles to the axis of the tool spindle, a manually operable switch mounted in said handle adjacent to the casing, and a socket mounted in the outer end of said handle in electrical connection with 105 said switch.

13. In an electric drill, the combination of 110 a motor, casing provided at one end with a bridge member, a perforated cover extending over the end of the motor casing, a motor in said motor casing, a gear casing mounted at one end of said motor casing, a center 115 plate separating said motor and gear casings, a tool spindle journaled in said gear casing and in operative connection with said motor, a bearing guide for said tool spindle supported in said center plate, a feed handle 120

125

130

mounted on the bridge member of said motor casing in axial alinement with said tool spindle, a non-rotative switch handle secured to said motor casing and extending at 5 right angles to the axis of said tool spindle, and a manually operable switch mounted in said switch handle.

In testimony, that I claim the foregoing

as my invention I affix my signature in the presence of two witnesses, this 4th day of 10 September A. D. 1913.

REINHOLD A. NORLING.
